SHOE

Max Gustin, New York, N. Y.

Application October 21, 1954, Serial No. 32,752

Term of patent 3½ years

(Cl. D7—7)

To all whom it may concern:

Be it known that I, Max Gustin, a citizen of the United States, residing at New York city, in the county of New York and State of New York, have invented a new, original, and ornamental Design for a Shoe, of which the following is a specification, reference being had to the accompanying drawing, forming part thereof.

In the drawing:

Fig. 1 is a three-quarter front perspective view of a shoe showing my new design;

Fig. 2 is a three-quarter rear perspective view of said shoe; and

Fig. 3 is a side elevational view of said shoe.

The dominant feature of my invention resides in the portions shown in full lines.

I claim:

The ornamental design for a shoe, substantially as shown and described.
